(57) **CLAIM**

The ornamental design for a pendant light module, as shown and described.

DESCRIPTION

FIG. 1 is a bottom perspective view of a pendant light module depicting our design;

FIG. 2 is a top perspective view thereof;

FIG. 3 is a left side view thereof, wherein the right side view is a mirror image of said left side view;

FIG. 4 is a bottom plan view thereof; and,

FIG. 5 is a top plan view thereof.
